UNITED STATES PATENT OFFICE.

TIMOTHY STEBBINS, OF DAVENPORT, IOWA.

DESIGN FOR A WELL-PIPE.

SPECIFICATION forming part of Design No. 33,462, dated October 30, 1900

Application filed August 7, 1899. Serial No. 726,477. Term of patent 14 years.

To all whom it may concern:

Be it known that I, TIMOTHY STEBBINS, a citizen of the United States, and a resident of Davenport, Scott county, Iowa, have invented and produced a new and original Design for Well-Pipes, of which the following is a specification, reference being had to the accompanying drawing, forming part thereof.

The drawing represents a side view of a section of a well-pipe, showing my new design.

The leading or material feature of my design consists of a sheet pipe A, having a longitudinal exterior seam *a* its entire length and having a cylindrical screw-threaded male nipple or joint *b* extending from one end and a female nipple or joint *c* in its other end. The

tubular shank *d* of nipple *c* is of about the same diameter as the bore of the pipe from the end of which it extends, and the portion of said nipple *c* between the end of the pipe ²⁰ and its end is bell-shaped or, in other words, stepped to a greater diameter, as shown.

Having described my invention, what I claim as new, and desire to secure by Letters Patent, is—

The design for a well-pipe, as herein shown and described.

TIMOTHY STEBBINS.
